(57) **CLAIM**

The ornamental design for a faucet, as shown and described.

DESCRIPTION

FIG. 1 is a top, front, left perspective view of a faucet showing my new design;

FIG. 2 is a bottom plan view thereof;

FIG. 3 is a right-side elevational view thereof;

FIG. 4 is a front elevational view thereof;

FIG. 5 is a left-side elevational view thereof;

FIG. 6 is a rear elevational view thereof;

FIG. 7 is a top, front, right perspective view thereof;

FIG. 8 is a top plan view thereof;

FIG. 9 is a top, front, right perspective view of a first alternate embodiment of my new design;

FIG. 10 is a bottom plan view thereof;

FIG. 11 is a right-side elevational view thereof;

FIG. 12 is a front elevational view thereof;

FIG. 13 is a left-side elevational view thereof;

FIG. 14 is a rear elevational view thereof;

FIG. 15 is a top, front, left perspective view thereof;

FIG. 16 is a top plan view thereof;

FIG. 17 is a top, front, right perspective view of a second alternate embodiment of my new design;

FIG. 18 is a bottom plan view thereof;

FIG. 19 is a right-side elevational view thereof;

FIG. 20 is a front elevational view thereof;

FIG. 21 is a left-side elevational view thereof;

FIG. 22 is a rear elevational view thereof;

FIG. 23 is a top, front, left perspective view thereof;

FIG. 24 is a top plan view thereof;

FIG. 25 is a top, rear, left perspective view of a third alternate embodiment of my new design;

FIG. 26 is a front elevational view thereof;

(Continued)

FIG. 27 is a right-side elevational view thereof;
 FIG. 28 is a top plan view thereof;
 FIG. 29 is a left-side elevational view thereof;
 FIG. 30 is a bottom plan view thereof;
 FIG. 31 is a top, rear, right perspective view thereof; and,
 FIG. 32 is a rear elevational view thereof.
 The broken lines in FIGS. 2, 10, 18, and 30 depict portions
 of the faucet that form no part of the claimed design.

1 Claim, 32 Drawing Sheets
